DESIGN FOR A TOY DUCK

Russell J. Awsumb, Hopkins, Minn., assignor to
Fibro Container Corporation, Minneapolis,
Minn., a corporation of Minnesota

Application February 11, 1944, Serial No. 112,543

Term of patent 7 years

(Cl. D34—15)

To all whom it may concern:

Be it known that I, Russell J. Awsumb, a citizen of the United States, residing at Hopkins, in the county of Hennepin and State of Minnesota, have invented a new, original, and ornamental Design for a Toy Duck, of which the following is a specification, reference being had to the accompanying drawing, forming a part thereof.

In the drawing:

Figure 1 is a front perspective view of a toy duck showing my new design;

Fig. 2 is a perspective view of the toy duck as seen obliquely from the side and front, and

Fig. 3 is a perspective view thereof as seen obliquely from the rear and side, the cord shown in Figs. 1 and 2 being omitted.

I claim:

The ornamental design for a toy duck, as shown.

RUSSELL J. AWSUMB.
